UNITED STATES PATENT OFFICE.

ANDREW C. WALTZ, OF PORT ARTHUR, ONTARIO, CANADA.

VALVE-SEAT GRINDER.

1,214,244.

Specification of Letters Patent. Patented Jan. 30, 1917.

Application filed July 19, 1916. Serial No. 110,055.

To all whom it may concern:

Be it known that I, ANDREW C. WALTZ, a citizen of the United States, and a resident of Port Arthur, in the Province of Ontario and the Dominion of Canada, have invented 5 a new and Improved Valve-Seat Grinder, of which the following is a full, clear, and exact description.

This invention relates to plumbers' apparatus and has particular reference to means for grinding or dressing the valve seats of water faucets or the like.

Among the objects of the invention is to provide a tool or set of tools to be carried 15 by a plumber or other artisan, or to be kept on hand in his shop for the purpose of repairing leaky faucets by regrinding or dressing the valve seats.

Another object of the invention is to provide a tool adapted to be operated either by hand or by motor and comprising a shank adapted to carry either or both of a plurality of cutters of different characters, such, for example, as a steel milling cutter for 25 roughing off, and a carborundum finishing or dressing cutter.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 35 to the accompanying drawings, in which like reference characters designate the same parts in the several views, and in which—

Figure 1 is a side elevation, partly broken away, of one adaptation of the invention 40 showing its relation to a valve whose seat is being reground; Fig. 2 is a vertical longitudinal section of the main cutter portion and having the milling cutter attached; Fig. 3 is a side elevation of the milling cutter; and Fig. 4 is a face view of the same.

Referring now more particularly to the drawings, I show the common form of faucet 10 having a valve seat 11 and a collar 12 threaded internally for the valve (not shown) and externally for the packing gland. The axis of the seat coincides with that of the collar.

The main element of my reamer or grinder consists of a body of solid abrasive material, 50 such as carborundum, shown at 13, preferably of cylindrical form. In the central

axis of this body is a threaded rod 14, the thread extending throughout the entire length of the rod and fixed rigidly to the abrasive material. A jacket or sleeve of thin 60 steel or brass is shown at 15 fitted upon the outer surface of the body 13 and approximately coextensive in length with the same. At the upper end the body is shown provided with a metal cap 16 screwed upon the rod 65 14 and having a flange 16' extending downwardly over the end of the carborundum, making a strong and rigid construction safeguarding the abrasive body from detrimental chipping or breaking. Both ends of the 70 rod project from the ends of the body. The upper end is adapted to receive the socket 17 of a handle 18 or other device, through which the reamer or grinder is adapted to be rotated. The lower end of the rod is 75 adapted to serve two important functions, first, it acts as a centering device by projecting into the outlet around which the valve seat 11 is located, thus insuring that the grinding end of the abrasive body will 80 act directly upon the circular upper surface of the valve seat. Secondly, the projecting lower end of the rod serves as a means for directly connecting to the body a disk like 85 milling cutter, shown at 19, for operation upon the valve seat when a deep flow is found therein. The teeth 20 of this cutter serve to quickly dress down or rough off the face of the valve seat if it is found to be irregular and then the disk is easily removable by unscrewing from the rod 14, leaving the end of the body 13 free and exposed for dressing or finishing the surface of the seat, 90 as indicated in Fig. 1.

The purpose of the sleeve 15 is to protect 95 the internal threads of the faucet from damage or abrasion due to the manipulation of the grinder, and it serves also as a means to protect the hard and more or less brittle body of the abrasive material from damage, 100 when out of use, as well as in use. The sleeve as well as the lower end of the rod may be cut off from time to time as may be required incident to the wearing off of 105 the active end of the carborundum.

I claim:

1. The herein described valve seat grinder comprising a round body of abrasive material, a centering device projecting downwardly from the center of the lower end 110 thereof, a screw threaded projection at the upper end thereof, a turning device remov-

ably connected to the threaded end aforesaid, and a reinforcing cap for the body between the turning device and the abrasive material, said cap embracing the entire upper end of the abrasive body.

2. In a valve seat grinder, the combination of a cylindrical body of abrasive material, a center rod threaded from one end to the other and projecting axially through said body and projecting therefrom at the upper and the lower ends, a metal reinforcing jacket protecting the abrasive body

around its curved surface, a reinforcing cap threaded upon the upper end of the center rod and embracing the end of the abrasive body and including also a flange projecting between the jacket and the upper end of the body, and a turning device connected to one threaded end of the rod.

ANDREW C. WALTZ.
